UNITED STATES PATENT OFFICE

160,777

MEDAL

Louis H. Dietzel, Kansas City, Mo., assignor to Kansas City Centennial Association, Kansas
City, Mo., a corporation of Missouri

Application November 21, 1949, Serial No. 6,165

Term of patent 3½ years

(Cl. D29—19)

To all whom it may concern:

Be it known that I, Louis H. Dietzel, a citizen of the United States, residing at 5736 Charlotte Street, Kansas City, in the county of Jackson and State of Missouri, have invented a new, original, and ornamental Design for a Medal, of which the following is a specification, reference being had to the accompanying drawing, forming a part thereof.

Fig. 1 is a front elevational view of a medal, showing my new design; and

Fig. 2 is an edge elevational view thereof.

The dominant features of the design reside in the portions shown in full lines.

I claim:

The ornamental design for a medal, as shown and described.

LOUIS H. DIETZEL.
